STEREO CASSETTE TAPE RECORDER CABINET

Peter Emmer, Buchenbronn, Germany, assignor to International Standard Electric Corporation, New York, N.Y.

Filed Oct. 12, 1973, Ser. No. 405,989

Term of patent 14 years

Int. Cl. D14—01, 03

U.S. Cl. D26—14 B

Fig. 2

Fig. 1

Fig. 3

Fig. 6

Fig. 4

Fig. 5

FIG. 1 is a front view of a stereo cassette tape recorder, showing my new design;

FIG. 2 is a bottom plan view of the stereo cassette tape recorder;

FIG. 3 is a top plan view of the stereo cassette tape recorder;

FIG. 4 is a rear view of the stereo cassette tape recorder;

FIG. 5 is a view of the left side of the stereo tape recorder; and

FIG. 6 is a view of the right side of the stereo tape recorder.

I claim:

The ornamental design for a stereo cassette tape recorder cabinet, substantially as shown and described.
